UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC-SWITCH MECHANISM.

1,394,397.

Specification of Letters Patent.

Patented Oct. 18, 1921.

Application filed November 18, 1918. Serial No. 263,073.

To all whom it may concern:

Be it known that I, REUBEN B. BENJAMIN, a citizen of the United States, residing at Chicago, in the county of Cook and State 5 of Illinois, have invented new and useful Improvements in Electric-Switch Mechanism, of which the following is a full, clear, concise, and exact description, reference being had to the accompanying drawing, forming 10 a part of this specification.

This invention relates to an electric switch mechanism and, more particularly, to an electric switch mechanism which is automatically operated by the action of a 15 door, window, or the like.

The object of this invention is to generally improve the construction of switch-operating mechanism of this type, and resides essentially in the production of improved 20 means which will prevent injury to the switch mechanism due to any improper operation or adjustment of the switch-operating mechanism; and, further, in an improved means for adjusting the switch-operating 25 mechanism.

Another object of the invention resides in an improved switch mechanism in which the switch-controlling appliances, or switch proper, together with the switch-operating 30 mechanism, are all united in a self-contained unit.

Other objects of the invention will become apparent from the following detailed description, the accompanying illustrations, 35 and the appended claims.

For the purpose of illustration, the preferred embodiment of the invention is illustrated in the accompanying drawings, in which—

40 Figure 1 illustrates the improved switch mechanism in position with respect to a door; the view being taken on the plane represented by the line 1—1 of Fig. 2;

45 Fig. 2 is a front elevation of the switch mechanism shown in Fig. 1 and illustrates the position that the switch takes with respect to the operating door or other moving element;

50 Fig. 3 is a section taken on the plane represented by the line 3—3 of Fig. 2, and illustrates the preferred form of switch used;

Fig. 4 is a detail of the switch taken on the

plane represented by the line 4—4 of Fig. 3; Fig. 5 is an alternative form of switch-operating mechanism and illustrates this 55 switch mechanism in position with respect to the door, the illustration being a plan view taken on the plane represented by the line 5—5 of Fig. 6;

Fig. 6 is a side elevation partly in section 60 of the same mechanism, taken on the line 6—6 of Fig. 5; and

Fig. 7 is a detail sectional view of the automatically-adjustable spring-operating 65 stop.

As illustrated in Figs. 1 to 4, the switch proper or circuit-controlling mechanism is inclosed in a housing 8 which is secured to a stationary door frame, window frame, or the like 9, by means of screws, such as 10 70 and 11. Connected to one side of the housing 8 is a conduit 12, by means of which the circuit-controlling conductors are admitted to the switch proper inclosed within the housing 8. Mounted on the base of the 75 housing 8 is an inclosing top or cover 13, which is secured to the base of the housing by means of the threads 14 illustrated in Fig. 3. Obviously, any suitable means for 80 attaching the cap 13 to the base could be utilized. The cap 13 is centrally apertured, said aperture carrying a threaded nipple 20, in which is loosely fitted a pin or rod 21 adapted for a reciprocating motion 85 within the nipple 20. Below the nipple 20 is preferably placed a suitable packing gland or gasket, such as 22, which serves to make the opening through which the pin 21 reciprocates waterproof, and thereby incloses the circuit-controlling mechanism or switch 90 proper within the housing 8 in a waterproof chamber.

The pin 21 carries at its lower end a flat plate or disk 23, which is continually held in contact with the button 24 of the circuit-controlling switch. Since the only opening into the housing 8 which contains the circuit-controlling mechanism or switch is rendered waterproof by means of a gasket 22, this mechanism is impervious to the effect of 100 moisture. Switches constructed in this manner are especially useful on board ship or in any climate in which the mechanism would be subject to the attacks of moisture;

the advantages of this structure and a more detailed description thereof having been given in my copending application.

- 5 The circuit-controlling switch-operating mechanism is mounted on the insulating base 25, on which is secured the mounting bracket 26, said bracket 26 being apertured to receive the sliding bar 27. This bar 27 carries at its upper end the operating button 24, and 10 fitted between the operating button 24 and the bracket 26 is a spiral spring 28. This spiral spring 28 is normally under compression and serves to maintain the button 24 in contact with the disk 23. Pivots 15 secured to pins or lugs 30 formed integral with the vertical member 31 of the bracket 26 is the movable bracket or arm 32 of the switch mechanism. The front face of the bracket 32 is apertured to receive a pin 33, which is 20 inclosed in a spiral spring 34 normally held in compression between the forward face of the bracket 32 and the rear end of the pin 34, which is pivotally attached to the sliding rod 27.
- 25 Mounted in the front end of the insulating block 25, as clearly illustrated in Fig. 4, are the contact terminals 37 and 38, to which are secured the upwardly-extending contact blades 39 and 40. The bracket 32 is arranged to move up and down under the action of the spring 34 and its associated elements, so that the side arms of the bracket 32 will make contact with the blades 39 and 40 and thereby close the circuit.
- 30 35 To operate the switch mechanism the button 24 is depressed against the compressive force of the spiral spring 28, thereby moving the rod 27 downwardly. In this movement the rear end of the pin 33 is carried downwardly with the rod 27, the pin being pushed forward through the front aperture in the bracket against the compressive force of the spring 34 until the pin 33 attains a substantially horizontal position, at which 40 time the energy in the compressed spring 34 will be exerted to draw the bracket 32 upwardly, thereby snapping the bracket 32 into position between the contacts 39 and 40 and thus closing the circuit.
- 45 50 When the compression on the operating button 24 is removed, the spiral spring 28 will return the moving parts of the switch mechanism to normal position, as illustrated in Fig. 3.
- 55 60 In order that the circuit-controlling switch mechanism hereinbefore described may be operated automatically by the action of a door or window, a switch-operating mechanism such as illustrated in Figs. 1 and 2 is provided. As clearly illustrated in these figures, this mechanism is attached to the housing 8. Thus, depending from one corner of the housing are the ears 41 and 42, between which is pivotally secured by means 65 of a pin 43 a bell-crank or rocker arm 44.

The upper end of the bell-crank carries a flat disk 45, which is adapted to move in the path of the operating pin 21. The lower end of the bell-crank 44 terminates in two perforated arms 46 and 47, which are adapted to receive the threaded operating pin 48. The threaded operating pin 48 carries between the arms 46 and 47 the nuts 49 and 50 and the spiral spring 51. The rod 48 is threaded to permit of adjustment of the position of said rod on the arms 46 and 47, the length of said rod 48 extending from the arm 46 determining, together with the compression spring 51, the amount of movement which will be given to the bell-crank 44 by 70 the operating door 52. The position of the nut 49 determines the length of the rod 48 which extends from the arm 46, and the nut 50 is utilized to determine the compression of the spiral spring 51; the rod 48 being loosely fitted in the arms 46 and 47.

75 Secured to the door 52 is a friction-plate 53 of any suitable character, preferably a steel or brass plate, which the end of the operating rod 48 strikes.

90 The following description of the operation of the mechanism will now be apparent from the preceding detailed description. When the door 52 is closed the friction-plate 53 will ride against the end of the pin 48 which will cause said pin to slide through the perforations in the arms 46 and 47, causing the nut 50 to press against the spiral spring 51, said pressure being applied through the spring 51 to the arm 47. The 95 pressure applied to the arm 47 will be exerted on the bell-crank 44, which will turn about its pivot 43 to cause the plate 45 to ride against the operating pin 21 of the circuit-controlling switch. The movement of 100 the disk 45 comprises a compound movement, the downward component of said movement acting upon the circuit-controlling operating mechanism situated in the housing 8 to operate it, as hereinbefore described, and thereby close the circuit of the switch mechanism. The pin 48 through the nut 50 will compress the spring 51, until the compressive force of said spring will be sufficiently great to operate the circuit-controlling mechanism inclosed within the housing 110 8. If for any reason this adjustment becomes disturbed or the movement of the door 52 is slightly altered, injury to the circuit-controlling switch inclosed within the 115 housing 8 is avoided by means of the operation of the compression spring 51. This compression spring acts as a protection and buffer in taking up this excess movement, the quality of the spring 51 being such that it 120 can be readily compressed by a force somewhat less than that required to injure the operating parts of the circuit-controlling apparatus contained within the housing 8.

125 130 It will be apparent from the preceding

description that whenever the door 52 is closed the circuit-controlling mechanism in the housing 8 will be automatically operated to close the circuit by means of the bell-crank 44 and its associated mechanism. Likewise, when the door is opened, the mechanism will be automatically restored to normal and the circuit opened.

It will also be apparent that if, for any reason, the switch-operating mechanism is out of adjustment, the delicate parts of the circuit-controlling switch inclosed within the housing 8 will not be injured, because of the resilient shock-absorber or buffer interposed between the primary mover 48 of the switch-operating mechanism and the bell-crank 44 which operates directly on the operating mechanism of the circuit-controlling switch.

Attention is now directed to the alternative form illustrated in Figs. 5, 6, and 7. In this form the circuit-controlling switch is contained within the housing 60, said housing being fitted with an opening to receive the conduit 61, through which the circuit conductors for controlling the circuit are led to the circuit-controlling apparatus within the housing 60. The circuit-controlling switch inclosed within the housing 60 is preferably of a type identically the same as that shown in Fig. 3. The housing 60 is secured to a bracket 62 by means of a bolt 63, the bracket 62 being secured to the door-frame 64 by means of screws 65. The switch-inclosing housing 60 is fitted with a cap 66, which is screw-threaded at 67 to the housing 60. Interposed between the housing 60 and the cap 66 and rigidly secured therebetween, because of the action between an annular rim 68 and the cap 67, is a flexible diaphragm 69 composed of a waterproof material, preferably pig skin.

The operating button 70 of the circuit-controlling switch inclosed within the housing 60 is mounted underneath the diaphragm 69, and the operating spring 71 of the switch mechanism serves to force this button to its normal position, as hereinbefore described in connection with Fig. 3; the spring 71 being sufficiently strong to distort or extend the diaphragm 69 so that the button 70 can be forced to its normal position under the influence of the spring 71. The cap 66 is centrally perforated, and in this perforation is slidably fitted a cylindrical switch-operating member or nipple 72, which is fitted with a flange 73 at its lower extremity, to prevent the nipple from falling out of the cap 66. The flange 73 also serves to hold the base 74 of the cylindrical member in position. The base 74 acts on the button 70 to operate the switch.

Inclosed within the cylindrical member 72 is a second cylindrical telescopic member 75, fitted with an annular flange at 76, said flange serving to limit the upper movement

of the telescopic member 75. A spiral spring 77 is interposed between the base 74 of the cylindrical member 72 and the upper wall 78 of the telescopic member 75, said spring 77 serving to spread apart to their farthest position the cylindrical member 72 and the telescopic member 75. The upper wall 78 of the telescopic member 75 is screw-threaded to receive a bolt 79, said bolt being adjustable vertically in the telescopic member 75 and serving to determine the movement of said telescopic member by the length of the bolt which extends beyond the wall 78. A lock-nut 80 is fitted on the bolt 79 for permanently securing said bolt in position after it has been adjusted.

The housing 60 and its associated mechanism is so positioned on the door-frame 64 that the end of the bolt 69 will contact with a friction-plate 81 secured to the door 82 when said door is moved into its closed position.

The operation of the switch-controlling mechanism will now be briefly described as follows: When the door 82 is moved to its closed position, the friction-plate 81 moves into contact with the end of the bolt 79, and, as the door continues to move, a similar movement will be acquired by the bolt 79 due to said contact. The bolt 79 will carry with it the telescopic member 75, which will be telescoped in the cylindrical member 72 against the action of the spring 77 until the compressive force of the spring is such as to overcome the action of the circuit-controlling apparatus contained within the housing 60. When this degree of compression is acquired by the spring 77, movement will be transferred to the operating button 70 of the circuit-controlling mechanism through the diaphragm 69, and this movement will continue until the switch is operated upon the complete closure of the door 82. The spring 77 is so designed that compression thereon will continue to the full extent of the telescopic movement of the members 72 and 75, before any force is exerted through these members to the operating button 70 of the circuit-controlling apparatus which will injure any of the delicate parts of the circuit-controlling switch. The spring 77 and the associated cylindrical member 72 and telescopic member 75 consequently act as a resilient buffer between the switch-operating mechanism and the circuit-controlling switch proper, thereby preventing injury to said switch through any slight improper adjustments of the switch-operating mechanism. Rough adjustment for controlling the movement of the switch-operating button 70 are obviously obtained by vertical adjustment of the bolt 79 in the telescoping member 75.

Switch-operating mechanisms constructed in accordance with the invention herein disclosed are useful for many purposes, but

are especially useful when it is desired to make the operation of the switch automatic upon the doing of some other act. Thus, the particular type of switch herein indicated may be used in any and all instances when it is desired to automatically open the circuit either to extinguish lights or to discontinue the operation of any other electrical apparatus when a door, window, or 10 the like is moved to the open position. Obviously the switch contact may be readily changed so as to reverse this operation and close the circuit when the door or window is opened.

15 Switches of the preferred type as herein shown, in which the circuit is closed when the door or window is closed, are especially useful on shipboard for the protection of the boat against attack by submarines. For 20 this purpose, it is desired to keep the exterior appearance of the boat in absolute darkness, while at the same time it is necessary to light certain portions of the interior of the boat so that the necessary activity on 25 the boat will not be interfered with. Under these circumstances, certain lamps on the boat may be readily turned on, the lamps being under the control of switches operated by the covers of portholes through 30 which the light emanating from the lamps controlled by the switches under the control of said portholes are visible from the outside. Under these circumstances it naturally follows that when any of these 35 portholes are opened the circuit including these lamps will be opened and the lights extinguished, thus insuring a darkened appearance for the exterior of the ship, notwithstanding the fact that lights are used 40 on the interior; this control being purely automatic because of the control of the lighting circuit by the movement of the porthole covers.

Obviously, this invention is not limited 45 to the specific and preferred embodiment thereof herein illustrated and described, but is capable of many variations and other applications which come within the spirit of the invention as set forth in the following claims.

I claim as new and desire to secure by Letters Patent of the United States:

1. A device of the character described comprising, in combination, a circuit-controlling switch, a casing for said switch, an operating plunger for said switch, said casing having an opening through which said switch can be inserted and removed with respect to said casing, a readily removable cap for closing said opening, said cap having an opening therethrough, a second plunger operating through the opening in said cap on said first plunger; and a resilient buffer interposed between said first 60 and second plungers.

2. In a device of the character described, in combination, a circuit-controlling switch; a casing for said switch; an operating plunger for said switch; a cap for said casing, said cap carrying a telescoping means including a resilient buffer, said telescoping means being operable through said resilient buffer to actuate the said plunger to operate said circuit-controlling switch. 70

3. In a device of the character described, in combination, a circuit-controlling switch, a casing for said switch, an operating plunger for said switch, said casing having an opening through which said switch can be inserted and removed with respect to said casing, a readily removable cap for closing said opening, said cap having an opening therethrough, a reciprocating plunger acting through the opening in said cap to actuate said first plunger, and a resilient buffer 80 interposed between said plungers. 85

4. A self-contained switch-operating mechanism including in combination a casing, a circuit-controlling switch mounted in said casing, said casing having an opening through which said switch can be inserted and removed with respect to the casing, a readily removable cap for closing said opening, said cap having an opening therein, an operating plunger for said switch, a second 90 plunger mounted in said cap and operating through the opening in said cap, and a resilient buffer interposed between-said plungers. 95

5. A self-contained switch mechanism containing, in combination, a casing; a switch mounted within said casing; an operating plunger for said switch; a cap for said casing; a waterproofing diaphragm interposed between said cap and said casing 105 to completely inclose said switch mechanism and its associated plunger; a second operating plunger; and a resilient buffer actuated by said plunger to operate said first plunger through said waterproofing 110 diaphragm to actuate said switch.

6. In a self-contained switch-operating mechanism, in combination, a casing; a switch located within said casing; an operating plunger for said switch; a cap for 115 said casing; means to inclose said switch in a waterproof inclosure; a second operating plunger; a resilient buffer actuated by said plunger, said resilient buffer acting upon said first plunger to actuate said switch. 120

7. A self-contained switch-operating mechanism comprising, in combination, a circuit-controlling switch; a casing for inclosing said switch; an operating plunger for said switch; a cap for said casing, said 125 cap being centrally apertured; a reciprocating plunger mounted in said aperture; a telescoping means mounted in said reciprocating plunger; a resilient buffer interposed between said telescoping means and said re- 130

ciprocating plunger; means to inclose said switch in a waterproof inclosure, the said telescoping means acting through said resilient means on said reciprocating plunger 5 through the waterproofing inclosure of the operating plunger of the switch to operate the same.

8. A self-contained switch-operating mechanism comprising, in combination, a 10 casing, a circuit-controlling switch mounted in said casing, said casing having an opening through which said switch can be inserted and removed with respect to said casing, a readily removable cap for closing said 15 opening, an operating plunger for said switch, a second plunger mounted in said cap, a resilient buffer interposed between said plungers, said second plunger acting through said resilient means to actuate said 20 first plunger to operate said switch mechanism, and adjustable means operable to determine the amount of movement initially transmitted to said second plunger.

9. A switch construction comprising a 25 switch mechanism, a casing for said switch mechanism, said casing having an opening through which said switch mechanism can be inserted and removed with respect to the casing, a readily removable cap for closing 30 said opening, said switch mechanism comprising a plunger inclosed by said casing and cap, said cap having an opening therein, a second plunger operating through the 35

opening of said cap on said first plunger, and yielding means interposed between said 35 plungers.

10. A switch construction comprising a switch mechanism, a casing for said switch mechanism, said casing having an opening through which said switch mechanism can 40 be inserted and removed with respect to the casing, a readily removable cap for closing said opening, said switch mechanism comprising a plunger inclosed by said casing and cap, said cap having an opening therein, a 45 second plunger operating through the opening of said cap on said first plunger, and adjustable means for varying the effect of said second plunger on said first plunger.

11. A switch construction comprising a 50 switch-mechanism, a casing for said switch mechanism, said casing having an opening through which said switch mechanism can be inserted and removed with respect to said casing, a readily removable cap for closing 55 said opening, said switch mechanism comprising a plunger inclosed by said casing and cap, said cap having an opening therein, a second plunger operating through the opening in said cap, yieldable means interposed between said plunger, and adjustable 60 means for varying the effect of said first plunger on said second plunger.

In witness whereof, I have hereunto subscribed my name.

REUBEN B. BENJAMIN.
